UNITED STATES PATENT OFFICE.

ASBJORN SONSTHAGEN, OF ESSEX, ENGLAND.

MACHINE FOR FOLDING PAPER.

Application filed January 13, 1923. Serial No. 612,390.

To all whom it may concern:

Be it known that I, ASBJORN SONSTHAGEN, a subject of the King of Norway, residing in Essex, England, have invented certain new 5 and useful Improvements in Machines for Folding Paper, of which the following is a specification.

This invention relates to improvements in and relating to paper folding machines 10 and it has for its object to provide a machine designed more particularly for folding paper to form dividing strips for use in packing chocolates and other sweetmeats, provision being made whereby the width 15 of the folded paper may be varied as desired.

The strips, when folded, may be of L or U shaped cross-sectional outline and provision is made for cutting same the desired 20 length.

In order that the invention may be the better understood drawings are appended in which:—

Fig. 1 is a side view of a machine according to this invention,

Fig. 2 is a plan,

Fig. 3 is a view seen from the opposite side to that illustrated in Fig. 1,

Fig. 4 is a sectional plan upon line A¹ A¹ 30 Fig. 1 showing more clearly the arrangement of the folders for varying the width of the fold,

Fig. 5 is a longitudinal section taken upon line A A Fig. 1,

Fig. 6 is an elevation of the machine as seen from the discharge or cutting end,

Fig. 7 is an end view as seen from the opposite end,

Fig. 8 is a longitudinal section on line X 40 X Fig. 1,

Fig. 9 is a front view showing more clearly the construction and arrangement of the cutting device.

Referring to the accompanying drawings 45 1 indicates a table or bed supported upon a foot or pedestal 2^a. Secured to the upper surface of table 1 are brackets supporting a spindle 2 upon which is mounted a roller 3. The spindle 2 has secured to it at its 50 inner end a disc 2^a formed of or faced with some suitable material or composition adapted to provide a good gripping surface for a second wheel 4, secured to a shaft 5, provided with fast and loose pulleys and carried in 55 bearings 6, said shaft being arranged at a

right angle to spindle 2. The spindle 2 is 60 slidable in its bearings and it has at its outer end a recess in which is placed a steel ball engaging a recess in the end of a lever 7 pivotally mounted in a bracket 8 disposed upon the side of the table 1. The other end 65 of lever 7 has formed upon it a stud engaging the interior of one end of a coiled spring 10 the opposite end of said spring engaging a stud upon a hand lever 11 moving over a plate 12 in which are provided a series of holes arranged upon a curved line having as its centre the fulcrum of the lever 11 the hand lever permitting the disc 2^a to be engaged with the wheel with varying degrees 70 of pressure, a pin or other device being provided for securing the lever 11 in its adjusted position.

The wheel 4 is also adjustable across the 75 face of the disc 2^a so that the speed of the roller 3, by which the paper is drawn through the machine, may be varied as desired.

Co-operating with the roller 3 is a second 80 roller 3^a carried in a bracket 13 disposed upon the underside of table 1 in which an opening 13^a is formed through which roller 3^a projects.

The bracket 13 comprises two side members having extending between them a part 85 13^b perforated for the passage of a stud 14 by means of which and nut 15 the said bracket is secured in position. In order to adjust the pressure of roller 3 against roller 3^a the bracket 13 at its outer end is provided 90 with a cross-member 16 of circular cross-section, which part engages slots formed on the end of an inverted U-shaped bracket also secured to the undersurface of table 1. The bracket 13 is thus capable of a radial movement permitting the aforesaid adjustment 95 to be effected.

As already stated the driving friction disc 4 is adjustable across the face of the disc 2^a and in order that this adjustment may 100 be effected there is provided a screwed spindle 15^a supported by the aforementioned brackets and having at one end a milled head 15^b. Mounted upon the spindle 15^a is a substantially inverted U-shaped body 18 the limbs of which engage between collars formed upon the boss of disc 4. By this means when the spindle 15^a is rotated in one or other direction a corresponding movement is imparted to disc 4 with the result 105 110

that the speed at which the paper is fed through the machine is retarded or accelerated.

One of the limbs of the body 18 is extended to form a pointer 18^a and arranged adjacent the said pointer is a scale 19 having divisions thereon corresponding to certain lengths of paper which will pass under the cutting knife, hereafter described, for each operation of said knife. The cutting knife, which is more clearly shown in Fig. 6, comprises two elements of which one comprises a steel plate or blade 20 recessed into the end of the bed 1 and a movable element comprising two arms 21 radiating from a central boss 22 secured to the driving shaft 5. The arms 21, at their upper ends, are provided with parts 21^a extending therefrom at a right angle to the body of said arms. The extensions 21^a are provided upon each side with lugs 23 through which pass set-screws 24 provided with lock-nuts 25. A blade, indicated by 26, is mounted by means of a screw 27 upon each extension of arms 21 the said screw passing freely through the blade and being screwed into the extension. The blades are thus free to pivot in the plane of their rotation upon the screws 27 their angular position being adjusted by means of the aforesaid set-screws so that they may be set to secure the most effective cutting action. 28 indicates spring plates introduced between the heads of screws 27 and said blades 25.

The paper, indicated by π , is carried by bobbin 29 supported on a spindle 30 carried by a horizontally disposed bracket 31 supported at one end from the vertical member of the pedestal. The bracket is slotted at 32 for the passage of the end spindle 30 which spindle is provided with a screw-thread engaging a nut 33 whereby the position of the spindle longitudinally of the bracket 31 may be varied as desired. Projecting from the inner face of the bracket 31 is a lug 34 bored for the passage of a rod 35 the lower end of which engages a hole or socket formed for it upon the base of the pedestal said rod being secured in said socket by means of a screw 36. Adjustably secured upon the rod 35 by means of a screw 37 is a boss 38 from the inner face of which projects a stud passing through a slot 40 in an arm 41 and by means of which stud said arm is adjustably secured to said boss. The arm 41 at its outer end, carries a roller over which the paper passes being guided upon each side in its passage from the roll to the paper by walls or partitions disposed upon each side of the web. Extending downwardly from the outer end of bracket 41 is a sheet metal plate or guide 31^a so bent or formed that the paper, in moving thereover, has given to it a half twist or turn as shown.

43 indicates an arm adjustably supported upon the rod 35 and slotted to receive the end of a spindle upon which is mounted a roller 45 around which the paper passes after leaving the plate 31^a the lower end of which plate is supported by the stud 46 projecting from the end of the arm 43. Also secured to rod 35, in a manner such as to permit of its adjustment longitudinally thereof, is a bracket 47 to which is secured by means of a thumb screw 48 a substantially L-shaped body 49 carrying the first folders by means of which the paper is doubled upon itself at a point coincident with the width of the paper or otherwise as will be hereafter more fully explained. Slidably mounted upon one arm of the body 49 by means of a thumb-screw 50 passing through a slot 51 is a body 52 having its inner edge shaped or recessed to a V-shaped outline, as shown, and with which body there co-operates a second body 53 having its inner edge correspondingly shaped a space being left between the two edges for the passage of the paper π which in its passage between the two bodies is partly folded upon itself as shown.

The body 52 is provided upon each side with extensions 54 between which the second body 53 is pivotally mounted upon a spindle 55 being secured against rotary movement by means of the thumb-screw 56 passing through one of the extensions 54 and into an extension 57 upon body 58. As the folder is adjustable transversely of the line of movement of the paper it follows that by setting it over to one side or other the paper will be folded upon its centre line or to one side or the other thereof so that the width of the respective folded portions may be varied as desired.

The paper π after leaving the folder just described passes under a plate 58 secured to the end of table 1 upon which there is also mounted a roller 59 over which the paper passes to the final folder secured to the upper side of the table. The form and construction of the final folder may be varied as desired. In the present instance it comprises a plate 60 having slots 60^a therein whereby it is mounted upon table 1 in a manner such as to permit of its adjustment transversely of the line of movement of the paper. The plate just referred to is turned over and inwards at its inner end at 60^b the forward edge being rounded as shown and the edge contacting with the paper being inclined. Secured in any convenient manner to the upper surface of the plate 60 and in spaced relationship thereto is a second plate 61 having its inner end of T-shaped outline said end being disposed within the turned over portion of the aforesaid plate 60 the said end engaging the inside of the paper as it is

being acted upon by the part 60^b of plate 60. Clamped to the underside of plate 61 by means of a screw 61^a thereon passing through slot 61^b in plate 61, is a third plate 5 61^c the forward or inner end of which acts as a stop engaging the under-edge of the paper as it is being folded and so preventing its displacement.

The paper after the folding is completed 10 passes between the feed rollers, already described, where it receives a final pressing before passing to the cutting knives.

The feed rolls to which reference has already been made are preferably mounted 15 on spindles which are inclined somewhat with regard to the center line of the paper, it has been found that by so arranging them, there is a slight tendency for the paper to lift somewhat from the surface 20 of the table facilitating the feed of the paper to the cutting knives.

In order to collect the cut paper a tray 25 may be provided, not shown, for which a support 62 may be arranged upon the pedestal of the table 1.

Claims:

1. A machine for folding and cutting paper comprising a bed, a shaft arranged longitudinally of said bed, a knife mounted upon one 30 end of said shaft and rotating in a plane at a right angle to the line of said bed, a blade fixed upon the end of the bed and co-operating with said knife, pulleys for driving said shaft, a friction disc slidably mounted upon said 35 shaft, means for moving said disc longitudinally of said shaft, a second shaft disposed at a right angle to said first shaft, a friction disc upon said second shaft engaging the edge of the first friction disc, a roller upon said second shaft, a second roller co-operating with said first 40 roller to feed the paper through the machine, means for varying the pressure of the second roller against the first roller, bearings for said first roller in which said spindle is slidably supported and means where- 45 by said spindle may be actuated to vary the pressure between the friction disc thereon and the friction disc of the first shaft, means for folding the paper longitudinally said folding means being adjustable transversely of the width of the paper to vary the width of the first fold and other folding means for effecting the subsequent folds.

2. A machine for folding and cutting paper comprising a bed, a shaft arranged 50 longitudinally of said bed, a knife mounted upon one end of said shaft and rotating in a plane at a right angle to the line of said

bed, a blade fixed upon the end of the bed and co-operating with said knife, pulleys for driving said shaft, a friction disc slidably mounted upon said shaft, means for moving said disc longitudinally of said shaft, a second shaft disposed at a right angle to said first shaft, a friction disc upon said second shaft engaging the edge of the first friction disc, a roller upon said second shaft, a second roller co-operating with said first roller to feed the paper through the machine, means for varying the pressure of the second roller against the first roller, means for folding the paper longitudinally said folding means being adjustable transversely of the width of the paper to vary the width of the first fold and other folding means for effecting the subsequent folds. 55 60 65 70

3. A machine for folding and cutting paper comprising a bed, a shaft arranged longitudinally of said bed, a knife mounted upon one end of said shaft and rotating in a plane at a right angle to the line of said bed, a blade fixed upon one end of the bed and co-operating with said knife, pulleys for driving said shaft, a friction disc slidably mounted upon said shaft, means for moving said disc longitudinally of said shaft, a second shaft disposed at a right angle to said first shaft, a friction disc upon said second shaft engaging the edge of the first friction disc, a roller upon said second shaft, a second roller co-operating with said first 75 roller to feed the paper through the machine, means for varying the pressure of the second roller against the first roller, bearings for said first roller in which said spindle is slidably supported and means where- 80 by said spindle may be actuated to vary the pressure between the friction disc thereon and the friction disc of the first shaft, means for folding the paper longitudinally said folding means being adjustable transversely of the width of the paper to vary the width of the first fold and other folding means for effecting the subsequent folds. 85 90 95

In testimony whereof I have hereunto set my hand in the presence of two witnesses.

ASBJORN SONSTHAGEN.
